(57) **CLAIM**

The ornamental design for a set of washing machine drum lifters, as shown and described.

DESCRIPTION

1. Set of washing machine drum lifters

1.1 : Perspective

1.2 : Front

1.3 : Back

1.4 : Left

1.5 : Right

1.6 : Top

1.7 : Bottom

1.8 : Reference

The broken lines indicate portions of the article that form no part of the claimed design; the dot-dashed lines in 1.8 represent boundary lines of drum so that the washing machine drum lifter inside drum can be seen and form no part of the claimed design.
